UNITED STATES PATENT OFFICE.

JAMES E. HAWKINS, OF GLENDALE, CALIFORNIA.

REFRIGERATOR.

1,403,320.

Specification of Letters Patent. Patented Jan. 10, 1922.

Application filed December 8, 1920. Serial No. 428,004.

To all whom it may concern:

Be it known that I, JAMES E. HAWKINS, a citizen of the United States, residing at Glendale, in the county of Los Angeles and 5 State of California, have invented certain new and useful Improvements in Refrigerators; and I do hereby declare the following to be a full, clear, and exact description of the invention, such as will enable others 10 skilled in the art to which it appertains to make and use the same.

The present invention relates to refrigerator or food-storage compartment, and is an improvement over the refrigerator dis- 15 closed in my Patent No. 1,328,625, granted Jan. 20, 1920.

It is the object of the invention to provide an iceless refrigerator using three elements, without the aid of ice, to maintain 20 a low atmospheric temperature within the enclosure, such elements being a structure of earthenware or plastic composition providing the compartment, an absorbent sheet disposed over said structure, and moisture 25 supplied to said sheet for saturating same, and the arrangement being such that air can circulate through the sheet or curtains formed thereby, whereby the interior of the compartment is cooled, and such circulation 30 of air also preventing the odorous foods from contaminating the others, in order that such odorous foods can be kept in the refrigerator without disflavoring other foods.

A further object is the provision of a 35 novel construction and assemblage of the component parts of the refrigerator structure, whereby such parts can be readily molded from clay, sand or similar material, or otherwise manufactured in a simple and 40 convenient manner, and the parts readily assembled to build up the refrigerator, as well as enabling the parts to be readily separated for purpose of cleaning, or replacing a broken part.

Another object is the provision of such 45 a structure having a novel water reservoir or container for holding drinking water, which is kept cool.

With the foregoing and other objects in 50 view, which will be apparent as the description proceeds, the invention resides in the construction and arrangement of parts hereinafter described and claimed, it being understood that changes can be made within

the scope of what is claimed without departing from the spirit of the invention. 55

The invention is illustrated in the accompanying drawings, wherein:—

Figure 1 is a perspective view of the im- 60 proved refrigerator.

Fig. 2 is a plan view thereof with the water reservoir and absorbent sheet re- moved.

Fig. 3 is a longitudinal vertical section 65 of the refrigerator.

Fig. 4 is a vertical transverse median sec- tion thereof.

In carrying out the invention, there is provided a pan 7, forming the bottom or base of the structure, and of elongated form, 70 with its ends rounded as shown, although the ends can be square or of other formation. The rim of the pan 7 has a drain faucet 8, preferably at one end for draining the water from the pan from time to time. 75

Mounted within the pan or base 7 is an upright rack or frame, including the up- rights 9 forming the ends of the refrigerator body, and said uprights are of arcuate section, as shown, to correspond with and 80 fit the ends of the pan 7, although said up- rights can be of various formations. The vertical edges of the uprights 9 project to- ward one another at the opposite sides of the pan 7, as seen in Fig. 2, and support the up- rights. These uprights 9 seat on the bottom 85 of the pan and in fitting against the ends of the rim of the pan are prevented from sliding away from one another.

The rack or frame includes a bottom shelf 90 10 and an upper shelf 11, which are similar form, being elongated and having their ends rounded or otherwise formed to fit within and abut the uprights 9, as seen in Figs. 2 and 3, and said shelves have shoulders 12 95 abutting the vertical edges of said uprights. These shelves being disposed and abutting the uprights 9, will hold said uprights sepa- rated, thereby maintaining the parts in place, and the lower or bottom shelf 10 has 100 depending lugs 13 at the ends thereof seat- ing on the bottom of the pan. The shelf 11 is supported on cross rods 14 carried by the up- rights and having their terminals embedded within the edge portions of said uprights, 105 so that the shelf 11 extends across and seats on said rods. If desired, two or more of the shelves 11 can be provided, and it will be

noted that the food stuffs or other objects can be readily placed within or removed from the refrigerator through the openings provided between the uprights at the opposite sides.

The top of the refrigerator comprises a water reservoir or container 15, which is of elongated form and its ends are preferably shaped to correspond to the uprights 9, and 10 said reservoir is seated on said uprights. The reservoir has a faucet 16, preferably at one end, so that the water can be drawn from the reservoir for drinking purposes. The reservoir has a cover or lid 17 for resting 15 on the rim thereof, and divided transversely, as at 18, near one end, to provide a removable piece or section 19 which can be readily raised or removed for filling the reservoir with water from time to time.

20 The pan 7, uprights 9, shelves 10 and 11, reservoir 15, and cover 17 are all molded from clay, sand, or similar material, and being of earthenware or plastic material, will aid in the cooling of the refrigerator by 25 moisture and air circulation, as well as providing for sanitation. The parts can be easily made and assembled, and should one of the parts become broken, it can be readily replaced. Furthermore, the parts can be 30 readily separated for purpose of cleaning them thoroughly.

A sheet 20 of suitable fabric, which is porous and of absorbent material, is disposed over the rack or frame, extending 35 transversely across the cover 17 of the water reservoir 15, and providing curtains 21 depending down the sides of the structure and closing the front and rear openings. These curtains or aprons 21 afford the circulation 40 of air through and within the food compartment, whereby to keep the contents cool and wholesome. A pocket piece 22 of similar material is secured on the upper portion of the sheet 20 above the cover 17, and forms a 45 pocket for a plate or slab 23 of earthenware similar to the other earthenware structure, which is fitted in said pocket and rests on the sheet 20, and the moisture is supplied from a bowl or receptacle 24 disposed in inverted 50 position with its rim or edge seating on the pocket piece 22 over the plate 23, whereby the water is compelled to seep from the bowl or receptacle under the rim thereof to be absorbed by the material. The upper surface 55 of the plate 23 can be grooved, as at 25, to provide for freer flow of water from under the bowl or receptacle to the sheet 20, and provides for a flow of the water to the curtains 21 by absorption and capillary attraction.

The bowl or receptacle 24 is readily applied by filling it in upright position and placing the sheet 20 and plate 23 over the receptacle, and then inverting the parts and 65 placing them on the other reservoir cover

17. This will prevent the water from spilling while the receptacle is being inverted.

The upper edge of the rim of the water reservoir 15 has slots 26 at opposite sides for the circulation of air through the water 70 reservoir, and the curtains 21 extend downwardly across said slots 26 to keep insects out of the water reservoir. This provision for the circulation of air through the reservoir will avoid sweating and condensation 75 therein, and the ventilation will also keep the water pure and cool, as well as aiding in keeping the curtains 21 moist and cool. One edge portion of the sheet 20 extends over the division 18 of the cover 17, but the piece or 80 section 19 can be readily removed for filling the reservoir with water when needed, and without disturbing the curtains 21 and water or moisture supplying device.

In using the refrigerator, with the parts 85 in place, as shown and described, the water will seep from the receptacle 24 under the edge or rim thereof into the fabric material, the flow being regulated by the plate 23, and grooves 25 in the upper surface 90 thereof, and the moisture will pass by capillary attraction and gravity down the curtains 21, thus providing films of moisture across the front and rear openings of the food compartment. The air can circulate 95 through said curtains, whereby the evaporation of the moisture will result in the interior of the compartment being cooled and maintained at a low temperature. This device is preferably located within a shady 100 airy location. The moisture is continually supplied to the curtains, controlled by the plate 23, so that a slow feeding of the water and moisture to the curtains is maintained, and said plate 23 can be readily removed 105 from the pocket 22 for the purpose of cleaning the plate or washing the sheet or covering 20.

The uprights 9 having their edge portion extending toward one another will seat on 110 the bottom of the pan or base 7 without danger of tilting, and the bottom shelf 10 holds the lower ends of said uprights in place against the ends of the pan 7, while the upper shelf 11 holds the upper ends of the 115 uprights apart, and when the reservoir is seated on the uprights the structure is substantial, and there is no danger of same falling over ordinary usage.

It will also be noted that the surplus water 120 will drip from the curtains 21 into the pan 7, and the water within the pan will prevent ants or other insects from entering the food compartment, although the curtains 21 can be readily lifted aside for access into such 125 compartment.

Having thus described the invention, what is claimed as new is:—

1. In a refrigerator, a rack having a top forming a water reservoir, and depending 130

porous curtains for the absorption of moisture extending downwardly from said reservoir across openings of the rack, said reservoir having slots for the circulation of air and said curtains extending across said slots.

5 2. In a refrigerator, a rack having a top forming a water reservoir, said reservoir having a cover, the rim of the reservoir having slots for the circulation of air, and a porous sheet extending across said cover and providing curtains depending across said slots and across openings of the rack.

10 3. In a refrigerator, a rack having a top forming a water reservoir, a cover for said reservoir, a porous sheet extending across said top and providing depending curtains for said rack, said cover being divided under said sheet and providing a removable section at one edge of said sheet.

15 4. In a refrigerator, a pan, separated earthenware uprights seated on the bottom of said pan and bearing against the rim thereof, a shelf between and fitting said uprights to hold them apart, a top seated on said uprights, a porous sheet extending across said top and providing depending curtains closing the openings between said uprights, and means for supplying water to said sheet above said top.

20 5. In a refrigerator, a base, separated earthenware uprights seated on the base and having their vertical edges extending toward one another to support the uprights, a shelf having its end portions fitted within said uprights between the edges thereof, a top seated on said uprights, a porous sheet extending across said top and providing depending curtains closing the openings between said vertical edges of the uprights, and means for supplying water to said sheet above said top.

25 6. A refrigerator comprising a pan, end uprights seated on the bottom of the pan and

bearing against the rim of the pan, a bottom shelf seated on the bottom of the pan and supported above said bottom, an upper shelf between the uprights, said uprights having their edge portions extending toward one another, cross rods carried by said edge portions of the uprights, across which the upper shelf extends to be supported thereby, the ends of the shelves being formed to fit within and abut said uprights, the lower shelf holding said uprights against said rim and the upper shelf holding the upper ends of the uprights apart, and a top seated on said uprights.

30 7. A refrigerator comprising a pan, end uprights seated on the bottom of the pan and bearing against the rim of the pan, a bottom shelf seated on the bottom of the pan and supported above said bottom, an upper shelf between the uprights, said uprights having their edge portions extending toward one another, cross rods carried by said edge portions of the uprights across which the upper shelf extends to be supported thereby, the ends of the shelves being formed to fit within and abut said uprights, the lower shelf holding the lower ends of the uprights against said rim and the upper shelf holding the upper ends of the uprights apart, a top seated on said uprights, said top forming a water reservoir, a cover for said reservoir, a porous sheet extending transversely across said cover and providing curtains depending to close the openings between said uprights, and means for supplying moisture to said sheet over said cover.

35 In testimony whereof I have signed my name to this specification in the presence of two subscribing witnesses.
